MIXING AND KNEADING MACHINE

Charles F. Beran, Tuckahoe, N. Y., and George Schneider, Montclair, N. J., assignors to Celanese Corporation of America, a corporation of Delaware

Application April 25, 1931, Serial No. 532,781

1 Claim. (Cl. 259—104)

Our present invention relates to mixing and kneading machines and more particularly to an apparatus for carrying out acetylizing and other chemical reactions in the manufacture of cellulose acetate.

In devices of this type, as heretofore commonly constructed, the stirrer arms, or agitators, were formed integral with the shafts attached to the driving means adapted to rotate said stirrer arms. This construction necessitated a complete dismantling of the machine where a stirrer arm had to be replaced for any reason, for example because of a worn shaft, such wear being caused by the pressure of the gland packing used on said shafts to prevent the escape of material or fumes.

Another factor which contributed to lower considerably the efficiency of these acetylizers was the ease, relatively speaking, with which the cooling medium penetrated into the inner shell of the trough through the joints, or seams, then, thus spoiling the charge. Whenever a leak was discovered, it was necessary to take the machine out of commission, dismantle practically the whole unit for the purpose of replacing the jointing material which consisted of asbestos or other suitable plastic and acid resisting compound. This dismantling included the removing of the stirring apparatus which was cumbersome because it was formed integral with the shafts. This was a decidedly costly procedure and it entailed considerable loss of time and labor, the machine remaining idle for two days and often for a longer period of time during the reconditioning thereof.

It is an object of this invention to provide an improved acetylizer which will be free from the above mentioned and other disadvantages and which will be especially simple and inexpensive in construction and efficient in operation.

In one aspect the invention comprises the provision in an acetylizer of a stirrer arm formed of a plurality of parts. The employment of a stirrer arm of this type permits of the use of different materials for the various parts. For the portion of the arm contained within the trough and which comes into contact with the charge, a material may be adopted which is most suitable to withstand the action of the acid used and which is highly resistive to the abrasive action incident to the mixing action. The shafts are desirably formed from a material which is relatively inexpensive and which is most efficient in withstanding the friction of the gland packings.

In another aspect the invention comprises an acetylizer having a trough the inner shell of which is formed without a joint or seam, the construc-

tion and arrangement being such that seepage of the cooling or heating medium into the charge through faulty joints is eliminated. To this end the trough may comprise a bronze casting forming an integral structure of an inner shell and, if desired, a jacket. Alternately, the inner shell may be made from sheet metal forming a single piece pan without joints. A jacket may be suitably secured to the pan.

Other objects and advantages, together with certain details of construction and combinations of parts, will be described in the specification and pointed out in the appended claim.

In the accompanying drawings:

Figure 1 is a front elevational view of the machine embodying our invention;

Figure 2 is a side elevation of the same, showing in dot-dash lines the trough in tilted position for emptying and cleaning purposes;

Figure 3 is a view, partly in section, taken on line 3—3 in Figure 2 showing the construction of the improved trough and stirrer arms;

Figure 4 is an end view, partly in section, showing the construction of the trough.

Figures 5 and 6 are side and end views, respectively, of a modified form of trough.

Like characters of reference indicate corresponding parts throughout the several views of the drawings.

Referring to the drawings, the reference numeral 7 indicates a base in which is suitably journaled a shaft 8. A trough 9 is pivotally mounted on the shaft and is adapted for tilting movement relative to the base 7 for the purpose of emptying and cleaning the same.

Referring to Figures 3 and 4, the trough is shown as a casting, preferably of bronze although any suitable acid resisting metal or alloy may be used, comprising an inner shell 11 and an integral jacket 12 through which a suitable cooling fluid is circulated by means of pipes 13. The inner shell is formed without the joints, or seams, heretofore present in troughs of this type thereby eliminating the possibility of damage to the charge by cooling fluid coming into contact with the charge through leaky joints.

In bearing boxes 14 suitably secured to end walls 15 of the trough are journaled shafts 16, 17, 18 and 19, which extend into the inner shell 11 through apertures 21 formed in said end walls. The stirrer arms 22 and 23 have integral collars, or hubs, 24 which are keyed to said shafts and are retained thereon by means of nuts 25. Caps 26 secured to hubs 24 by screws 27 and stuffing boxes 28 fixed to the trough by means of bolts 29 are

provided for each shaft to prevent leakage of material or fumes. Extending longitudinally along the bottom of the inner shell 11 substantially centrally thereof and secured thereto by screw bolts 5 31 is a saddle 32 which cooperates with the stirrer arms 22 and 23 during a mixing operation, as is well understood in the art. By the construction outlined above it will be readily observed that we have provided a stirrer arm assembly 10 wherein the shafts which normally wear down first may be replaced with loss of very little time and without the necessity of removing the stirrer arms from the trough. All that is required is to loosen and withdraw the shaft and to insert a 15 new one.

The trough is provided with a cover 33 in which there is a large opening 34 for the purpose of facilitating the cleaning of the trough. A lid 35, adopted to be suitably clamped down while a 20 charge is being worked, is fitted to said opening. There is also provided a smaller opening 36, normally closed, and through which any material can be charged into or discharged from the trough. For the purpose of flushing out the rust and other 25 accumulations which frequently form in the jacket of the trough, apertures 37 are formed in the bottom thereof, said apertures being normally closed by covers 38 suitably attached by screws 39.

30 Referring to Figures 5 and 6, there is disclosed a modified form of trough which differentiates from the type of trough shown in Figures 3 and 4 by being constructed in two main parts which are made of rolled sheet metal rather than as a 35 single casting. The modification provides for a single piece inner shell 41 with the complete absence of joints, said shell having a plurality of suitable brackets 42 welded or otherwise secured to the outer surface thereof. When required, a 40 jacket 43 may be attached to the brackets by means of bolts 44 and nuts 45, the construction being such the trough structure is able to withstand considerable pressures.

The stirrer arms are driven by a suitable gear 45 arrangement, generally indicated by reference numeral 46, which is adapted to rotate the arms

at different speeds, forward and reverse, as is well understood in the art.

The trough is tilted by a driving arrangement (not shown) which by means of a chain 47 rotates a gear 48 fixed on a shaft 49 journaled in bearings 51 formed in the upper extremities of upright members 52 attached to base 7 by cross-bars 53. The shaft 49 rotates the gears 54 and 55 suitably secured thereto which drive chains 56 and 57, respectively. One end of each of these chains is secured to a bracket 58 attached to the trough by bolts or rivets 59, the other end carrying a counterpoise 61 of suitable weight.

5 10 15 Means are provided to automatically lift the lid 35, hinged to the cover 33 at 62, during the tilting movement of the trough, said means consisting of a rod 63 attached at one end to an eye-bolt 64 in the lid 35, the other end being mounted for pivotal movement on the shaft 49 by means of a loop member 65. It will be readily understood that as the trough is tilted the lid will be raised and held in open position by means of the above arrangement.

20 25 For the purpose of discharging the contents from units of large capacity, the trough may be provided at its lowest point with a discharge valve. In such an arrangement, a tilting means is, of course, unnecessary and accordingly the labor and time required for tilting the trough is saved.

30 Having thus described our invention what we claim as new and desire to secure by Letters Patent of the United States is:

35 In an acetylator, the combination with a one-piece trough having shafts extending therein, of a stirrer arm having integral hubs detachably secured to said shafts, means carried by said hubs for preventing leakage of material from said trough, a cover for said trough, said cover having an opening therein, a lid normally closing said opening, means including a shaft for tilting said trough and means for raising said lid during a tilting movement of said trough comprising a rod secured to said lid and to said shaft.

CHARLES F. BERAN.

GEORGE SCHNEIDER.
